UNITED STATES PATENT OFFICE.

ALBERT E. LYCAN, OF PARIS, ILLINOIS.

FENCE.

SPECIFICATION forming part of Letters Patent No. 628,102, dated July 4, 1899.

Application filed October 29, 1898. Serial No. 694,970. (No model.)

To all whom it may concern:

Be it known that I, ALBERT E. LYCAN, a citizen of the United States, residing at Paris, in the county of Edgar and State of Illinois, have 5 invented a new and useful Fence, of which the following is a specification.

The invention relates to improvements in fences.

The object of the present invention is to 10 improve the construction of wire fences, more especially the means for anchoring the ends of a fence, and to provide an anchoring device which will permit the fence-wires to be readily adjusted to maintain them at the desired 15 tension.

The invention consists in the construction and novel combination and arrangement of parts, as hereinafter fully described, illustrated in the accompanying drawings, and 20 pointed out in the claims hereto appended.

In the drawings, Figure 1 is a perspective view of a portion of a fence constructed in accordance with this invention. Fig. 2 is a longitudinal sectional view, partly in elevation. 25

Like numerals of reference designate corresponding parts in both the figures of the drawings.

1 designates a series of horizontal fence-wires, preferably composed of twisted strands; 30 but single wires may be employed, as will be readily understood, and they are supported at intervals by vertical stays 2, constructed of wire and preferably twisted around the horizontal fence-wires, as shown. The ends 35 of the fence-wires are secured to an attachment bar or post 4, which is capable of adjustment to tighten the fence-wires simultaneously, and the said wires, which may be 40 permanently attached to the vertical bar or post 4, can be connected with the same by any desired form of wire-stretcher, so that the wires may be adjusted independently of one another. The attachment bar or post is provided 45 at intervals with perforations arranged in pairs, and the ends of the fence-wires are strung through the perforations and twisted, as shown.

The vertical bar or post 4 is suspended 50 above the surface of the ground by means of inclined anchoring rods or wires 6 and 7, extending upward and inward from an anchor

8 and passing through upper and lower eyes 9 and 10 of a post 11. The anchor 8, which may be constructed of any suitable material— 55 such as stone, metal, or the like—is embedded in the ground beyond the fence, as clearly illustrated in Fig. 2 of the accompanying drawings, and the lower ends of the anchoring-rods may be connected with the anchor by 60 any suitable means, such as extending them through a perforation of the anchor or forming an eye or coil for embracing the latter.

The eyes 9 and 10 of the post 11 are preferably formed by staples, and the converging 65 bracing-rods, which extend beyond the staples, are adjustably connected with the bar or post 4 by horizontal rods or bolts 12 and nuts 13. The rods or bolts 12 are provided at their outer ends with eyes 14, through which 70 the adjacent ends of the bracing wires or rods are passed and secured by twisting them around the body portions of the bracing-rods, as shown. The other ends of the horizontal rods or bolts 12 are threaded and extend 75 through openings of the bar or post 4, washers being interposed between the same and the nuts 13. By adjusting the nuts 13 the fence-wires may be drawn to the desired tension. 80

The post 11 forms a portion of a section 15 of the fence, and the said fence-section 15 is composed of the post 11 and an end post 16 and a series of horizontal bars or rails 17, which project beyond the post 11 to close the 85 space between the same and the post or bar 4. The projecting portions 18 of the rails 17 are of sufficient length to permit the necessary adjustment of the bar or post 4 without uncovering the space between the same and 90 the adjacent post of the fence-section.

The invention has the following advantages: The anchoring means, which are exceedingly simple and inexpensive in construction, are especially adapted for use in connection with 95 wire fences where the wires are under tension and exert a severe longitudinal strain on the holding devices. The anchoring-rods, which extend through the eyes 9 and 10, are adjustably connected with the bar or post 4, 100 which is suspended above the surface of the ground, so that it may be readily moved toward the post 11, and the adjusting devices arranged at the ends of the anchoring-rods

enable the fence-wires to be simultaneously stretched and maintained at the desired tension.

Changes in the form, proportion, and minor details of construction, such as varying the construction of the means for adjustably connecting the anchoring rods or wires with the attachment bar or post 4, may be resorted to without departing from the spirit or sacrificing any of the advantages of this invention.

What is claimed is—

1. The combination of a fence-post provided with eyes arranged near its top and bottom, the downwardly-converging longitudinal anchoring-rods passing through the eyes of the fence-post and provided at their upper ends with adjusting devices, a movable bar or post 4 connected to the adjusting devices and suspended by the same above the surface of the ground, and fence-wires connected to the bar or post 4, substantially as and for the purpose described.

2. The combination of a fence-post provided with eyes, the downwardly-converging longitudinal anchoring-rods extending through the eyes and having their outer ends

embedded in the ground, an anchor connected to the outer ends of the rods, fence-wires, and the movable bar or post 4, having the fence-wires attached to it and adjustably connected with the upper ends of the anchoring-rods, substantially as described.

3. The combination of a fence-section composed of fence-posts and horizontal rails, the latter being extended beyond the inner fence-post, eyes mounted on the inner fence-post, the downwardly-converging longitudinal anchoring-rods passing through the eyes and having their outer ends embedded in the ground, said rods being provided at their inner or upper ends with adjusting devices, a movable bar or post suspended by the said adjusting devices, and fence-wires connected with the movable bar or post, substantially as described.

In testimony that I claim the foregoing as my own I have hereto affixed my signature in the presence of two witnesses.

ALBERT E. LYCAN.
